UNITED STATES PATENT OFFICE.

FREDERICK B. SPOONER, OF BROOKLYN, NEW YORK.

STOCKING-FRAME.

SPECIFICATION forming part of Letters Patent No. 240,802, dated April 26, 1881.

Application filed December 22, 1880. (No model.)

To all whom it may concern:

Be it known that I, FREDERICK BRITTAN SPOONER, a citizen of the United States, residing at Brooklyn, in the county of Kings and State of New York, have invented certain new and useful Improvements in Stocking-Frames, of which the following is a specification.

The object of this invention is to provide as thin, light, and inexpensive a frame as possible, and which shall at the same time be capable of adjustment, so that both the foot and leg, or either of them, may be expanded or contracted to suit various sizes of hose, but at all times retain the true relative outline of both foot and leg.

Heretofore artificial limbs have been employed for exhibiting stockings. These, however, stretch the stocking and take up too much room to exhibit a large quantity in a small space, as they cannot be set as closely together as in my case, and furthermore cannot be used to so great an advantage in drying stockings as it would if constructed in skeleton form, so as to give the air more chance to circulate directly through the article on the frame.

Figure 1 represents a side view, showing a wire frame whose front outline is adjusted by means of a cam and whose rear outline is adjusted through the agency of spring or looped connecting-bars. Fig. 2 is a side view of a modification of the same. Fig. 3 is a side view of a modification of the same when made of solid material.

Similar letters of reference indicate corresponding parts.

In the case here presented, A represents a skeleton-frame, preferably made of wire, the contour of whose outline resembles the true form of a neat foot and leg without any distortion in thickness. The said frame, commencing at the upper extremity, a, extends downward, and in one continuous piece follows the contour of the foot and leg, and the other extremity, a'', of the said piece of wire, after forming the top of the frame, extends centrally down the leg and terminates at the toe, where it is soldered fast. It will here be noticed that at the bottom of the heel the wire is bent inward in the form of a large ring or loop, b, so that should it be necessary to in-

crease or diminish the length of the foot it can be accomplished by spreading or contracting the same. The cross-bars c c c, connecting the central wire with the rear wire, are also made in like manner with loops in their centers, so that they may also be expanded or contracted to vary the size of the calf and back of the leg generally. The forward part 60 of the said wire frame, from the toe upward, acts as a spring whose tendency is to press outward. This spring is connected by two parallel bars, d' d', which are linked or pivoted in their respective positions, as shown in 65 the drawings. The said front of the leg is moved by means of the cam e, or its equivalent, pivoted to the central wire. The said cam having a grooved or channeled face and bearing against the free end of the forward wire 70 enables the same to be held in any desired position. The loop f at the top is formed by making an eye and bending the same to one side, so as to form a hook.

In Fig. 2, which represents a modification 75 of the above, I dispense with the use of the spring or free end forming the front of the leg, and make the exterior of the frame a continuous wire; and in order to allow the same to be adjusted to any width of leg or length of foot, 80 I employ cross-braces c' c' c' c', also provided with loops, and a loop or ring, b, being formed at the heel, in like manner to that above described.

I do not limit myself solely to constructing 85 the above frames of wire, but also propose making them of sheet metal, wood, pasteboard, or other suitable material.

In making the frame of wood, as shown in Fig. 3, the frame is made in two pieces, g g', 90 which are connected by two parallel bars, h h', whose extremities are pivoted to their respective pieces, as shown.

It will here be observed that that portion forming the front of the leg is so constructed 95 that when it is closed up to its smallest form its exterior line will be flush with the top i and the inner faces of the two parts g g' made to match. The toe being on the forward piece, g, and its bottom being on the same line as the sole of the foot on the piece g', it allows the foot to be lengthened at the same time and with the same movement as that of the leg 100 without interfering with the true line of the

sole of the foot. The said front piece, *g*, is held outward in any desired position by means of the pawl *k*, which is pivoted on the piece *g'* and bears upon the top of *g*.

5 It will here be observed that from the peculiar form of the cap of the knee there is a projection which, in conjunction with the swell of the calf, assists materially in holding the stocking from falling in longitudinal shrinking.

10 I am aware that devices have been made of wire for drying and stretching hose; but such have not been made capable of adjustment. These I do not claim.

Having thus described my invention, what I 15 claim as new, and desire to secure by Letters Patent, is—

1. The combination, in a device for drying and stretching hose, of the parallel braces *d'* and cam *e*, forming a movable connection

between the toe and top of the leg, whereby 20 the same may be adjusted to any width of hose, substantially as shown and described.

2. The combination, in a device for drying and stretching hose, of the parallel braces *d'* 25 and cam *e* with the looped braces *c c c* and loop *b*, for the uses and purposes substantially as shown and described.

3. In a stocking-frame, the combination, with the continuous wire frame A *a''*, of the looped connecting-bars *c c c*, loop *b*, and hanger *f*, 30 when constructed and arranged in the manner and for the uses and purposes substantially as described and shown.

FREDERICK B. SPOONER.
